UNITED STATES PATENT OFFICE.

MAHLON E. LAYNE, OF HOUSTON, TEXAS.

PIPE-LIFTER.

No. 889,139.

Specification of Letters Patent.

Patented May 26, 1908.

Application filed October 24, 1905. Serial No. 284,181.

To all whom it may concern:

Be it known that I, MAHLON E. LAYNE, a citizen of the United States, residing at Houston, in the State of Texas, have invented certain new and useful Improvements in Pipe-Lifters, of which the following is a specification.

My invention relates to means for lifting and holding pipes used in wells and the like, and particularly to means upon such pipe lifters for gripping the pipe tightly in place and holding it against turning in the lifter. The primary objects of my invention are to provide a clamp or lifter with means to prevent the pipe from turning therein and to better support the lifter and hold the pipe more securely, and to provide means for gripping both a section of pipe and the coupling that connects it with the next section. Other objects and advantages will hereinafter appear. I have shown the invention in preferred forms in the accompanying drawings, wherein—

Figure 1 is a top plan view, and Figure 2 is a side elevation of my improved pipe lifter with a piece of pipe and the clutch attached thereto, Figure 2 showing the clutch released;

Figure 3 is a central vertical section of the same with my improvements applied thereto;

Figure 4 is a central vertical section and half side elevation of a modified form of pipe lifter having a double clutch embodying my improvement attached thereto so that both the pipe and the coupling may be held against turning, and

Figures 5 and 6 are a plan and side elevation respectively of the modified form of pipe lifter shown in Figure 4.

The pipe lifter itself comprises, essentially, two horizontally swinging pivoted jaws 5 and 6 which are joined together by a vertical pivot pin 7 at one side, and on the other side have respectively projecting lugs or arms 8 and 9, which, when brought together are held by a clip 10 pivoted in one of the jaws and designed to rest in a notch on top of the arms of the lifter, as shown in Figures 1 and 2, and presents a flat surface 11 upon which the coupling collar of the pipe rests to hold the said link 10 in place as more clearly shown in Figure 3. The rear end of one of the jaws of the lifter also has a projecting arm 14, and both the arms 8 and 14 are notched so as to engage a rod 13 which may form a fixed part of the table or platform

upon which the operating tools are supported for manipulating the pipe in lowering or lifting it from the well.

It will be understood that in ordinary operation a section of pipe having a coupling sleeve thereon as shown in Figure 3 will be surrounded by the two jaws 5 and 6, and will support the pipe by abutment against the lower side of the sleeve 18 of the pipe. Referring to Figures 1, 2 and 3, particularly, it will be seen that I have mounted upon the pivot pin 7 which hinges the two jaws 5 and 6 a revoluble clutch 19 which is provided with teeth 20 to engage the coupling sleeve 18 of the pipe. The block 19 has an upwardly extending head 19^a which is of such form as to allow of turning it with a wrench, and it is held upon the pin 7 by means of a cotter pin 21 as will be understood. I prefer to make the clutch 19 with teeth on four of its sides, so that it will engage the pipe against turning in either one of two directions, and when reversed will present a fresh set of teeth in case the ones on one side are worn. From Figure 3 it will be seen that I have provided in the clutch block 19 a pair of recesses which contain pointed pins 22 pressed downward by coil springs and designed to set in countersunk notches or holes provided in one of the jaws 5 or 6, as may be convenient. This is to hold the clutch block 19 temporarily in place in whatever position it may be put. The form of the clutch, it will be observed, is such that the effort of the pipe to revolve it around its pivoting pin 7 will cause it to clutch the pipe more tightly and therefore will securely hold the same. At the same time the jaws 5 and 6, themselves, are prevented from turning by their engagement with the stationary cross-bars 13, which may be any part of the platform or table for supporting the pipe.

In Figures 1, 2 and 3, I have shown an improved form of the pipe lifter in which the jaw 8 is made wide and provided with a notch 12, to engage the rod 13, and also with an elongated slot in which the clip or link 10 is mounted in such a manner that it will have sufficient play to fit in its place nicely when the pipe sleeve 18 comes down and rests upon the flat portion 11. The elongated slot also permits of the link being raised and thrown back for the purpose of unlocking the jaws. The lower portion of the arm 9 is cut away as shown in Figure 2, so as to allow the jaws to be opened when the link is thrown back.

- In Figure 4, 5 and 6 I have shown a slightly different manner of securing the lifter upon the rods 13, and also a provision for holding both the pipe 17 and the accompanying sleeve 18 against turning. The lifter in this instance is held in position upon the rod 13 by means of downwardly projecting lugs 12^a, formed upon the arms 8 and 14, said lugs abutting against the inner sides of the rod 13.
- 10 The arm 8 is further provided with a rest or abutment 8^a for the arm 9, said abutment 8^a projecting from the arm 8 a distance equal to the thickness of the arm 9. The pipe 17 is prevented from turning by means of an additional clamping block 19^b mounted upon the pivot pin 7 below the pipe coupling 18. Said block is provided with teeth 20^b which engage the pipe 17 and prevent its turning in a manner similar to the toothed block 19.
- 15 20 The jaws 5 and 6, in all cases, have laterally extending lugs 15 with eyes which engage the lifting links 16 for engagement with the elevator chain hook as will be understood.

Having thus described my invention and 25 illustrated its use, what I claim as new and desire to secure by Letters Patent, is the following:

1. A pipe lifter comprising a pair of pivoted jaws, and a rotatable cam clutch fixed 30 upon one of said jaws and adapted to engage the member inclosed between them with a wedging action and hold itself in secure engagement therewith.
2. The combination with two lifter jaws 5 35 and 6, of the pivoted cam clutch block 19, provided with a plurality of engaging teeth adapted to engage the member to be supported in the lifter, to prevent the same from turning, substantially as described.
- 40 3. The combination with a lifter comprising a pair of relatively movable jaws having

means to hold them closed, and a pivot pin for securing the jaws together of a clutch block mounted upon the pivoting pin of said jaws and adapted to engage the member to 45 be held in the jaws.

4. The combination with a lifter comprising a pair of jaws and a pivot pin for securing them together, of a double faced clutch block mounted upon the pivoting pin of the jaws 50 and having teeth adapted to engage the member to be held on either side of the medial line in order to prevent the pipe from turning in either direction, substantially as described. 55

5. A lifter comprising a pair of pivoted jaws having laterally extended arms and notches in said arms to engage bars or other stationary parts of a table or platform, and a clutch to engage the member in the jaws. 60

6. In a pipe lifter the combination with a pair of jaws for engaging the pipe and a pivot pin for securing the jaws together, of a clip for holding the free ends of the jaws together, and a double ended clutch mounted upon the 65 pivoting pin of the jaws and adapted to engage the pipe coupling either side of the center line when the pipe is supported in the jaws.

7. In a pipe lifter comprising a pivot pin, a 70 pair of jaws pivoted thereon, and a pair of clutches mounted upon the pivoting pin of the jaws and adapted to engage respectively the pipe and the coupling for two sections of pipe, substantially as described. 75

In testimony whereof I have hereunto signed my name in the presence of the two subscribed witnesses.

MAHLON E. LAYNE.
